(57) **CLAIM**

The ornamental design for a handrail support, substantially as shown and described.

DESCRIPTION

FIG. 1 is an isometric view of a handrail support showing my new design.

FIG. 2 is an enlarged front view of the handrail support of FIG. 1.

FIG. 3 is a back elevational view thereof.

FIG. 4 is a left elevational view thereof.

FIG. 5 is a right elevational view thereof.

FIG. 6 is a top plan view thereof; and,

FIG. 7 is a bottom plan view thereof.

The broken lines shown in FIGS. 1-7 illustrate environment and form no part of the claimed design.

1 Claim, 5 Drawing Sheets

FIG. 1

FIG. 2

FIG. 5

FIG. 4
